US0D1036833S

(12) **United States Design Patent** (10) **Patent No.:** **US D1,036,833 S**
(45) **Date of Patent:** **** Jul. 30, 2024**

(54) **SHOE MIDSOLE PERIPHERY**

(71) Applicant: **Skechers U.S.A., Inc. II**, Manhattan Beach, CA (US)

(72) Inventor: **James Frantz**, Torrance, CA (US)

(73) Assignee: **Skechers U.S.A., Inc. II**, Manhattan Beach, CA (US)

(**) Term: **15 Years**

(21) Appl. No.: **29/920,591**

(22) Filed: **Dec. 12, 2023**

Related U.S. Application Data

(57) **CLAIM**

The ornamental design for a shoe midsole periphery, as shown and described.

DESCRIPTION

FIG. 1 is a front perspective view of an embodiment of a shoe midsole periphery in accordance with my new design;

FIG. 2 is a front elevation thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

Broken lines shown in the drawings represent portions of the shoe and form no part of the claimed design.

1 Claim, 7 Drawing Sheets
